CLAIM

The ornamental design for an in-store marketing sign, as shown and described.

DESCRIPTION

FIG. 1 is a front view of one embodiment of the in-store marketing sign.

FIG. 2 is a top view of the in-store marketing sign embodiment of FIG. 1.

FIG. 3 is a bottom view of the in-store marketing sign embodiment of FIG. 1.

FIG. 4 is a left side view of the in-store marketing sign embodiment of FIG. 1.

FIG. 5 is a right side view of the in-store marketing sign embodiment of FIG. 1; and,

FIG. 6 is a back view of the in-store marketing sign embodiment of FIG. 1.

The dashed lines in FIGS. 1-6 do not form any part of the claimed design for the in-store marketing sign.
